PRINTING AND EMBOSsing MACHINE

Edward Roberts, Jr., Hohokus, N. J., assignor to
 Roberts, Cushman & Company, New York, N. Y.,
 a corporation of New York

Application July 23, 1935, Serial No. 32,689

5 Claims. (Cl. 197—6.4)

This invention relates to printing or embossing machines, in which pens or articles to be embossed or printed are held in position to enable a typewheel to be selectively operated, and pressed against the article to be embossed.

This invention consists more particularly in the means of holding the article, said means being of simple construction, and readily operable, so as to firmly hold the article when operated upon, and permit its ready insertion and removal. For this purpose pivoted jaws are provided which, when open, permit the ready insertion of the article, and when closed securely hold the article and hook it in position, the jaws being locked in position, while the article is being operated upon. This co-relationship of parts is set in an environment so as to enable the article while thus held in position, to be moved step by step, to enable the letters or numbers to be printed, to be successively applied thereto.

The invention will be further described hereinafter in connection with the embodiments thereof shown in the drawings, and will be finally pointed out in the claims.

25 In the accompanying drawings—

Figure 1 is a side view of an embodiment of the machine, with the invention utilized therein;

Figure 2 is a plan view thereof, taken on line 2—2 of Figure 1;

30 Figure 3 is a front view of Figure 2;

Figure 4 is a central longitudinal section of Fig. 2, taken on line 4—4 of Fig. 2;

Figure 5 is a transverse section of Fig. 2, taken on line 5—5 of Fig. 2;

35 Figure 5a is a sectional view, taken on line 5a—5a of Figure 5;

Figure 6 is a detail transverse section of the jaws, taken on line 6—6 of Fig. 2;

Figure 7 is a detail plan view taken on line 7—7 40 of Fig. 5; and

Figure 8 is a detail view of a guard device, for controlling the entry of the type into the article to be stamped, taken on the line 8—8 of Fig. 1.

Similar characters of reference indicate the 45 same parts throughout the various views.

Referring to the drawings and more particularly to Figure 1, the base 10, is suitably secured to a table or the like by screw bolts 11. To the base 10 is pivoted at 12, a type wheel casing 13 having a handle 14 to move it downwardly in the direction of the arrow 15. Within the casing 13 is a type wheel 16 having at its periphery, type 17, the wheel being rotatable on its axis 18, by a handle 19. A suitable electric thermal device 20, heated by means of the conductors 21, serves in

a manner well known to heat the type 17. A spring 22, secured at one end 23 at 24, and exerting its force through its other end 25, against a shoulder 26 of the casing 13, serves to move the casing 13 to its initial or normal position after it has been moved to its operative position by the handle 14. The type 17 of the type wheel 16 is visible through an opening 27 of the casing, and the selected type protrudes through the casing 13 at 28, the type 17 moving in the direction of 10 the arched arrow 29 when the casing is moved downwardly by the handle 14. The type to be used is selected by the rotation of hand wheel 19. No novelty is claimed in any of these parts.

The article 30 to be pressed, stamped, printed 15 or embossed, is held by jaws 31, so as to expose the surface of the article to be operated upon as clearly shown in Figure 1, when the selected type comes down in the path of the arched arrow 29.

These jaws 31 are supported on a carriage 32 20 having extensions 33, entering guide ways 34 of the casing 10. The jaws 31 are opened or closed by the drawing up of a spindle 35 within a sleeve 50, by means of a handle 36.

At the ends of the jaws 31, there are provided 25 clippers 38, which serve to hold a piece of gold paper or the like, upon the jaws 31, and over the article to be operated upon.

The carriage 32 is moved longitudinally in its 30 guide ways 34, step by step by a mechanism now generally referred to as 40, which mechanism is set in operation with each downward movement of the casing 13, so as to enable the next selected type to consecutively follow and aline with and to be disposed alongside the previously printed 35 character.

Referring now to Figures 5 and 6, the jaws 31 are provided with a seat portion 41, and an enclosing portion 42. Each jaw at its lower portion is pivoted at 43 to the carriage 32, by virtue of 40 which the jaws are loosely supported, and are freely movable in respect to each other.

The jaws 31 are provided with openings 44 through which passes the spindle 35, which at one end is provided with an enlargement 45 having a curved surface 46 engaging a corresponding bore portion 47 in one of the jaws 31. As seen in Fig. 5, the openings or bores 44 are slightly larger in diameter than the diameter of the spindle, whereby a certain lost motion between the parts 50 exists. A similar enlargement 47a with a curved surface 48 engages a corresponding bore portion 49 in the other jaw 31. The spindle 35 extends beyond this second enlargement and passes through a sleeve 50. To the free end of the 55

spindle is secured the handle 36. By the turning of the handle 36, the jaws 31 are either brought together as shown in Figure 1, or away from each other as shown in Figure 5. At the enlargement 45, there is provided a pin 51 thereon, which enters an opening 52 of the jaw 31 to prevent the spindle or bolt 35 from turning. The action of the spindle 35 overcomes the action of helical spring 54 seated at its ends in recesses 55 of the jaws 31, which spring has a tendency to keep the jaws open.

In Figure 6 is also shown the gold leaf holding clippers 38, which are pivoted to screws 56 (shown in Figure 1), and have in addition to the parts 15 already described, extending portions 57, which are shaped to be able to be conveniently manipulated by hands of the operator, and are forced outwardly by the springs 58 having one end seated in recesses 59 and the other ends pressing against 20 the extensions. The result of the action is that the free ends 60 of these clippers 38 hold the desired gold paper of the like against the top surface of the jaws.

Referring now to Figures 1, 2 and 7, there is 25 secured to the lower end of the casing 13, a lever arm 62 to which is pivoted a lever 63, (heretofore generally referred to by the mechanism 40, in Figure 1), and to this lever 63 is secured a spring 64, having its other end fastened to the 30 extension 55 of the housing 13. The lever 63 is bent so as to present a longitudinal portion 66 to a plate 67, having an upward extension 68 passing through the portion 66, and a pin 69 passes through the extension 68, so as to connect these 35 parts together. The plate 67 is pivoted to the base 10 by the pivot 70 (see Figure 7). The plate 67 has two elongated openings 71, through which pass uprights 72 of rods 73, suitably guided on the base 10. These rods have sharpened pawl-like 40 ends 74 which engage a ratchet or rack 75 forming part of the carriage 32. Only one of these pawls 74 engages the rack 75 at one time. The plate 67 is acted upon by a spring 76 passing around the pivot post 70, which spring has its free 45 ends 77 engaging the uprights 72. The carriage 32 is provided with a downward extension 78, to which is attached one end of a spring 79, having its other end secured to the base 10, as shown in Figure 4. By this mechanism generally referred 50 to by the character 40, the carriage 32 is moved step by step, with every downward movement of the handle 14. The lever 63 moves the plate 67 and the rocking movement thereof causes one or the other part 73 to engage the rack 75, and 55 by this escapement action the carriage 32 and the jaws 31 holding the pen or the like, are moved so as to be in position to receive the next type action. After this printing operation has been completed, the carriage can be moved back to its 60 initial position, so as to remove the pen or the like, and a new one can be inserted, and the operation repeated.

The carriage 32 abuts in one position of its movement against a stop 32^a, shown in Figure 4. 65 It is detachably fastened to the plate 33 by means of a pin 91 supported by the carriage 32 and this pin 91 engages a recess 92 of the plate 33. The pin 91 extends upwardly to handle 86, suitably gripped by a screw-threaded thumb button 88 70 adjustable against a spring plate 88 secured at 85 to the carriage. A spring 90 is interposed between an enlargement 90^a of the pin 91 and a shoulder 85 of the carriage, which spring 90 serves to press the pin 91 downwardly into the recess 92. 75 The carriage 32 is movable along the extension

slide 94. When the carriage is so moved outwardly on the extension 94, and then returned to the position shown in Figure 4, the protruding pin 91 will first strike the beveled portion 93 of the plate 33, and ride on the same until it comes over the recess 92, and drop therein and thus interlock the carriage 32 and plate 33. In order to move the carriage 32 outwardly on the extension 94, it is first necessary to lift the pin 91 out of its recess 92 by raising the thumb-nut 89 upwardly.

In Figure 5, the limit of the swinging movement of the left-hand jaw is indicated by the lines passing through the pivot 43, and referred to by the phrase "limits of swinging."

The electric heater 80 is arranged so as to be close to the type wheel 16, in order readily to heat the type 17, as shown in Figure 1 and Figure 8. The thermostat 20 is placed against the type wheel 16. The thermostat is arranged in a housing 81 to receive a spring-pressed block having a bore in which the thermostat 20 is located. The springs are indicated by 82.

In order to prevent the type 17 from pressing into the body of the article to be stamped, a safety guard is provided. This consists of a pivoted lever 83 which has a pivot rod 84, held on an adjustable support 87 having a rod 95 slideable in the type wheel casing 13. A screw 96 acting upon the rod 95 fixes the rod tightly in the desired position. A spring 97 presses the guard or lever 83 downwardly as shown in Fig. 8. The guard 83 extends to the type wheel 16, over a shoulder 98 of the type wheel and proximate to the side of the type. When the stamping takes place the guard is pressed against the article to be stamped and the guard is then pressed by the article against the shoulder 98, and thereby the entrance of the type 17 into the article itself is limited in extent.

The improved device is very simple, in that it is only necessary to open the jaws to receive the article to be operated upon, and when the article has been placed between the jaws, to close the jaws, and thereby securely hold the article, during the stamping operation.

My invention has been illustrated and described with some degree of particularity, but it is understood that changes may be made in the form of details and in the construction and arrangement of parts without departing from the spirit and scope of the invention or the scope of the appended claims.

I claim:

1. In an embossing machine, means for holding the article to be stamped comprising pivoted jaws, means for opening or closing the same to receive and to hold the article to be operated upon and means carried by the jaws for holding a sheet in a position overlying the article.

2. In an embossing machine, a carriage, two jaws, each pivoted to the carriage, said jaws having a seat portion and a holding portion for the article to be operated upon, a spindle passing through each jaw, a spring normally holding the jaws open, means closing the jaws against the action of the spring and means carried by the jaws for holding a sheet in a position overlying the article.

3. In an embossing machine, a base, a carriage on said base, jaws pivoted to the carriage, means for opening and closing the jaws, means for moving the carriage step by step and means carried by the jaws for holding a sheet in a position bridging the upper portions of the jaws.

4. In an embossing machine, a pair of pivoted

jaws, resilient means for retaining the jaws in open position, a spindle passing through both jaws, adapted to be rotated for the opening or closing of the jaws against the action of the spring, said jaws having a seat portion for the article to be operated upon, a holding portion enveloping part of the article to be operated upon and means carried by the jaws for holding a sheet in a position bridging the upper portions of the jaws.

5. In an embossing machine, a base, a carriage movable rectilinearly on the base, a pair of article clamping jaws independently pivoted to the carriage at opposite sides of the median plane thereof, printing means forming part of said embossing machine and arranged to imprint on said article along said median plane, said jaws

having registering transverse openings therethrough adjacent the pivots of the jaws with countersunk shoulders at the outer sides of the jaws, a clamping bolt engaging through the transverse openings of the jaws and having a head on one end with an abutment face for engaging the adjacent shoulder, a thumb nut threaded on the other end of the bolt and having a follower portion with an abutment face for engaging the opposite shoulder, and an expanding spring between the jaws for urging the same apart and forcing the shoulders of the jaws against said abutment faces for maintaining the jaws in equi-distantly spaced relation from the opposite sides of the median plane of the carriage 15 in various adjusted positions of the thumb nut.

EDWARD ROBERTS, JR.
